CLANCY M. ROGERS, OF KANSAS CITY, KANSAS.

PICTURE TOY.

Application filed April 16, 1927. Serial No. 184,383.

This invention relates to improvements in toys and more particularly to a toy possessing educational value.

One of the objects of the present invention is to provide a toy of the class referred to above which will be extremely simple in construction and inexpensive to manufacture and which will embody, in a minimum space, a maximum number of instructive or educational representations which may be selectively brought to view.

The toy embodying the invention consists essentially of a plurality of disks which are interleaved and so arranged with respect to one another and to a cover disk having a sight aperture therein, that different matters to be displayed to view, printed or otherwise depicted upon the disks, may be brought to position within said opening, selectively, and the invention contemplates a novel interleaving of the disks and a novel relative arrangement thereof which will provide for the display of a maximum number of display areas upon the disks and a great variety in comparison with the number of disks and the area thereof.

Another object of the invention is to so relatively arrange the disks that when once assembled they cannot be disarranged through careless handling of the toy but will, on the other hand, be maintained in their proper assembled relation.

Other objects will be made apparent as the description of the invention progresses and in the drawings representative examples of embodiments of the invention are illustrated although the invention is susceptible of a wide range of modification.

In the accompanying drawings: Fig. 1 is a plan view of one side of a toy constructed in accordance with the present invention;

Fig. 2 is a similar view looking at the opposite side thereof;

Fig. 3 is a view similar to Figure 2 illustrating the disks comprising the toy relatively rotated and disclosing a portion of an auxiliary display disk which is employed in connection with certain of the disks bearing pictures or other matter to be displayed;

Fig. 4 is a sectional view taken substantially on the line 4—4 of Figure 2, all portions of the structure in rear of the plane of the section being omitted for the sake of clearness

and the view illustrating the relative arrangement of the interleaved disks;

Fig. 5 is a perspective view illustrating a fragment of one of the disks and the finger tab associated therewith, the view showing adjacent portions of the disk relatively distorted or separated to better illustrate the construction, in full lines, and illustrating in dotted lines the normal condition of the disk;

Fig. 6 is a detail sectional view taken substantially on the line 6—6 of Figure 5 looking in the direction indicated by the arrows;

Fig. 7 is a plan view of the cover disk of the toy;

Fig. 8 is a similar view of the auxiliary display disk referred to above;

Fig. 9 is a schematic perspective view of several of the disks illustrating the manner in which they are interleaved, the cover disk being omitted as also the finger tabs for the said disks;

Fig. 10 is a plan view of one side of one of the display disks;

Fig. 11 is a plan view of the opposite side thereof;

Fig. 12 is a view similar to Figure 10 illustrating another disk;

Fig. 13 is a view similar to Figure 11 illustrating the reverse side of the disk shown in Figure 12;

Fig. 14 is a view similar to Figures 10 and 12 illustrating another one of the display disks;

Fig. 15 is a view similar to Figures 11 and 13 illustrating the reverse side of the disk shown in Figure 14;

Fig. 16 is a plan view illustrating a modified form of the toy;

Fig. 17 is a similar view looking at the opposite side thereof;

Fig. 18 is an edge elevation of the toy shown in Figure 16;

Fig. 19 is a diametric sectional view taken substantially on the line 19—19 of Figure 17 looking in the direction indicated by the arrows;

Fig. 20 is a plan view of the cover disk of the form shown in Figures 16 and 17;

Fig. 21 is a similar view looking at the opposite side of the cover disk;

Fig. 22 is a view similar to Figure 20 illustrating one side of one of the display disks;

Fig. 23 is a similar view looking at the reverse side of the disk shown in Figure 22;

Fig. 24 is a view similar to Figure 22 illustrating one side of another one of the display disks;

Fig. 25 is a view similar to Figure 23 illustrating the reverse side of the disk shown in Figure 24.

In the embodiment of the invention illustrated in Figures 1 to 15 inclusive, the toy consists essentially of an assemblage of disks 10 possessing different characteristics and adapted to serve individual purposes and one of these disks is indicated by the numeral 1 and will be referred to as the cover disk. Several others of the disks indicated in general 15 one by the numeral 2, another by the numeral 3, and a third by the numeral 4, will be referred to as display disks, and a fifth disk, indicated in general by the numeral 5, will be referred to as an auxiliary display disk. 20 The disks 1, 2, 3, 4 and 5 are formed centrally with openings indicated respectively by the numerals 6, 7, 8, 9 and 10, and an eyelet or any other suitable swivel element indicated by the numeral 11 is secured through the 25 openings of the disks and serves as a means for connecting the disks in assembled relation for relative rotative movement. As the disks are assembled in a peculiar manner the construction or formation of each disk 30 will first be described and I will then describe the manner in which they are assembled and the manner in which they are manipulated so as to produce different display effects, and at this point it may be noted that 35 while the disks are herein shown as circular in marginal contour, they may possess any other desired contour.

The disk 1, which is referred to above as the cover disk, may have any matter desired represented upon its face although this disk is 40 preferably left plain and the disk is formed, in the embodiment illustrated, with a display opening 12, which, in the illustrated form of the invention, is preferably of substantially 45 elliptical form, the minor or narrower end of the opening being located next adjacent the axis of the disk and the broader end being located adjacent the periphery of the disk. The disk is provided, preferably opposite the 50 broader side of the opening 12, with a finger tab indicated by the numeral 13 so that the opening 6, the opening 12, and the finger tab 13 are in radial alinement.

The display disks 2, 3 and 4 are structurally 55 identical and these disks are formed with arcuate incisions indicated respectively by the numerals 14, 15 and 16, the incisions extending on an arcuate line from the openings at the axes of the respective disks to the peripheries of the respective disks, or these incisions may form a straight line if so desired. The disks 2, 3 and 4 are provided at their peripheries with finger tabs indicated respectively by the numerals 17, 18 and 19 and it 60 will be observed by reference to Figures 10

to 15 inclusive that these finger tabs project radially from the peripheries of the respective disks and that the incisions 14, 15 and 16 are extended medially through the respective tabs as indicated respectively by the 70 numerals 20, 21 and 22. As an example of the present invention, the disk 2 and likewise the disk 4 may bear, upon one face, a map 23 as in the instance of the disk 2, and upon the other face a pictorial representation 24 as in 75 the instance of the disk 4, the map and pictorial illustration occupying, if desired, the entire area of the said face of each respective disk. The disk 2 bears upon its other face, and which face, in the assembled 80 relation of all of the disks, as will presently be described, is the face which is presented next to the cover disk 1, or in the general direction of said cover disk, with a plurality of display areas indicated by the numeral 85 25 which areas may be outlined or not as desired. In any event each area will constitute a pictorial or similar representation or display and, in the specific embodiment of the invention shown, each area may 90 embrace a letter of the alphabet and some object the name of which has its initial letter represented by the letter referred to as represented in the area. This is of course merely 95 representative of the invention and various pictorial illustrations, verses, prose, quotations from authors, or in fact any instructive matter may be represented as the subject matter of each display area. As will be observed by reference to Figure 11 in which the 100 display areas 25 are more clearly illustrated and likewise by reference to Figure 15, which is similar to Figure 11, the display areas are arranged in an annular series concentric to the axis of the disk upon the face of which 105 they are represented and they are spaced with respect to each other and of such dimensions that they may be individually viewed through the display opening 12 of the cover disk 1 when brought into position opposite said 110 opening or in registration therewith. The disk 4 is provided upon its face which is shown in Figure 15 and which is the face opposite that shown in Figure 14, with an annular series of display areas 26 corresponding 115 in their general arrangement and character to the areas 25.

The disk 3, shown in Figures 12 and 13, differs from the disks 2 and 4 in that instead of being provided with display areas, it is 120 formed with an annular series of stencils indicated by the numeral 27, which stencils may be representative of various articles or animals.

The disk 5 is somewhat different in its construction from the disks 2, 3 and 4 and constitutes an auxiliary display disk. The said disk 5 is of segmental form or in other words 125 does not describe a complete circle but is provided in one side with a segmental recess or 130

opening indicated by the numeral 28 and which may be of any desired angular width as for example, 90 degrees. The disk 5 preferably bears upon one of its faces a series of 5 display areas 29 which are concentric to the opening 10 in the disk, the disk being arranged, as will presently be explained, between the disks 2 and 3, and the face which bears the display areas 29 being that face 10 which is presented toward the disk 2. Preferably the walls of the recess or opening 28 will be curved to correspond to the curvature of the incisions 14, 15 and 16 in the disks 2, 3 and 4. At its periphery and at 15 one side of the opening 28, the disk 5 is formed with a radially outwardly extending finger piece indicated by the numeral 30.

Referring now to Figures 2, 3, 4 and 9 of the drawings it will be observed that the disks 20 2, 3, 4 and 5 are helically interleaved. That is to say the disks are interfitted or interleaved at the incisions 14, 15 and 16 of the disks 2, 3 and 4 and the opening 28 of the disk 5, this helical interleaving being shown in 25 Figure 4 of the drawings in which the several disks have been illustrated on a much exaggerated scale and in a more or less schematic manner to illustrate this feature and yet avoid confusion, it being understood that the disks 30 will be relatively thin, being of cardboard, celluloid, or other thin and suitably stiff material, and that the disks will all lie close to one another in their interleaved relationship, so that the cover disk which is the lower- 35 most disk in Figure 4, will not be spaced from the underside of the disk 2 at that portion of the disk which is in overlapping relation to the disk 4, it being observed that the disk 5 is interleaved with the disks 2 and 3 or in 40 other words lies between these disks and that the disk 2 is next beneath the disk 1, as shown clearly in Figure 1 of the drawings.

The disks 2, 3 and 4 are provided at corresponding sides of their incisions 14, 15 and 45 16 respectively with spring metal friction clips indicated respectively by the numerals 31, 32 and 33, and it will be observed by reference to Figure 2, that the clips 31 and 32 are designed to frictionally engage over the 50 disks 3 and 4 respectively at the said sides of the incisions. This engagement of the clips with the companion disks is a frictional engagement and serves to restrain the disks against relative displacement under conditions 55 which will presently be explained. It may be stated at this point, however, that whereas the clips 31 and 32 upon the disks 2 and 3 are designed to effectively frictionally coact with the disks 3 and 4, the clip 33 upon 60 the disk 4 is adapted to coact frictionally with the disk 2 when, for example, the disk 2 and the disk 3 remain in the position shown in Figure 2, but the disk 4 is rotatably adjusted through nearly 360 degrees at which 65 time the clip 33 will frictionally coact with

the disk 2 at the margin of the incision 14 therein.

It will now be evident that with the parts in the position shown in Figures 1 and 2 of the drawings, the disks 2, 3, 4 and 5 may all 70 be rotatably adjusted with respect to the disk 1 with a step-by-step movement so as to successively display within the bounds of the opening 12 in the disk 1 the display areas 25 upon the disk 2 which disk, as previously 75 stated, is next adjacent the disk 1. This will bring all of the finger tabs 17, 30, 18 and 19 to a position at the left side of the finger tab 13 of the disk 1 in Figure 1 of the drawings instead of at the right hand side as illustrated in said figure and at this time the last 80 display area 25 of the said disk 2 will be exposed within the opening 12. At this time the finger tab 19 will be next adjacent the finger tab 13 of the disk 1 and by grasping 85 this tab and holding the tabs 17, 30 and 18 and the finger tab 13 stationary, the display areas upon the disk 4 may be successively brought opposite the display opening 12, the finger tab 19 being finally brought to position 90 beside the finger tab 17. The finger tab 18 is then grasped, and rotary motion is imparted to the disk 3 so as to bring the stencils 27 thereon successively into position to be displayed through the opening 12, this movement being continued until the finger tab 18 is in position beside the finger tab 19. The finger tab 30 may next be grasped and rotary motion imparted to the disk 5 to successively bring the display areas 29 thereof 95 into position opposite the opening 12, this movement being continued until the said finger tab 30 is in position beside the finger tab 18. At this time the opening 28 in the disk 5 will be in position opposite the opening 2 100 and therefore the operation previously described may be repeated. In this manner all of the display areas upon the disks 2, 4 and 5 and the stencils in the disk 3 may be displayed to view through the opening 12. 105 While any one of the display areas is in position opposite this opening, a piece of thin paper may be inserted between the disk 1 and the disk bearing the display area and a tracing may be made, by the child using the 110 toy, of the object or the like displayed upon the surface of the exposed disk within the bounds of the said display area thereof, or, if the disk 3 is being adjusted and one of the stencils 27 is opposite the opening 12 and 115 within the bounds of the same, a piece of paper may be inserted between the disk 3 and the disk 4 and a pencil point may be run along the walls of the opening defining the stencil so as to mark upon the paper a tracing 120 of the represented figure or object. It will also be understood from the foregoing description that the complete displays 23 and 24 upon the reverse faces of the disks 2 and 4 may be displayed by adjustment of 125 130

the disks through the medium of the respective finger tabs. In this connection it will be observed by reference to Figure 2 that in the adjustment of the parts shown therein substantially the entire reverse face of the disk 4 is exposed to view. If it is desired to exhibit the matter upon the corresponding face of the disk 3, this may be accomplished by holding the finger tabs 13, 17, 30 and 18 stationary and rotatably adjusting the disk 4 through the medium of the tab 19 so as to cause this disk to enter between the disks 2 and 3. From the foregoing description of the manner of adjusting the several disks, in using the toy, it will be evident that the disks 2, 3, 4 and 5 are movable either individually or collectively with respect to the disk 1 and that the movement of the disk is restricted to either side of the finger piece 13 of the disk 1. In other words it is only contemplated that the disks be rotatably adjusted in either a clockwise or anti-clockwise direction through not more than that part of a complete revolution which would effect travel of the respective finger pieces 17, 18, 19 or 30 from one side of the finger piece 13 to the other side thereof without passing the said finger piece 13.

As previously stated the incisions 14, 15 and 16 are extended as at 20, 21 and 22 through the finger tabs 17, 18 and 19 and this is necessary in order to permit of the assemblage of the disks in mutually helically interleaved relation. However it is likewise essential that the slit portions of the said tabs 17, 18 and 19 be united and this is preferably accomplished in the manner clearly shown in Figures 1, 2, 5 and 6 of the drawings and particularly in the two latter figures wherein the numeral 34 indicates a binding element in the nature of a piece of adhesive tape which is folded transversely medially and disposed with its plies overlapping the opposite sides of the tab to which it is to be applied and adhesively united thereto, the plies being preferably of such a length that they will extend a short distance inwardly of the tab and be adhesively united to the respective disk. However in order that the disks may be mutually interleaved in the manner stated, it is necessary that the binding members 34 have their plies formed with slits indicated by the numeral 35 which extend from the end edges of the plies of the member 34 to a point adjacent the fold therein, which fold is indicated by the numeral 36 and receives the outer end edge of the finger tab to which the member 34 is applied. It will be evident, at this point, from an inspection of Figures 1 and 2 of the drawings that the finger tabs 17, 18 and 19 may mutually overlap to the extent of approximately one half the width of the tabs.

The embodiment shown in Figures 16 to 25 inclusive is much simpler than the embodiment just described and comprises a disk 37

corresponding to the cover disk 1 of the previously described embodiment and a plurality of display disks indicated one by the numeral 38 and the other by the numeral 39 although, while only two of the display disks are shown, any desired number may be employed as will be evident from the description which is to follow. Likewise, as will be evident by reference to Figures 20 and 21 of the drawings, the cover disk 37 constitutes also a display disk. The disk 37 is provided with a display opening 40 and the outer face of the disk is plain, the disk being provided upon its inner face however with a plurality of display areas indicated by the numeral 41 and arranged in an annular series concentric to the axis of the disk. The disk is provided with a finger tab 42 and the disks 38 and 39 are provided with finger tabs 43 and 44 respectively. The disks 37, 38 and 39 are provided centrally with openings 45, 46 and 47 respectively and an eyelet or other swivel element 48 is secured through these openings and serves to connect all of the disks in the superposed interleaved relation shown in Figures 18 and 19 of the drawings, the disk 37 being uppermost in these figures and the disk 39 lowermost. The disks 38 and 39 are provided with openings 49 and 50 which constitute display openings and are of the same contour and dimensions as the opening 40 and it will be observed by reference to Figures 20 to 25 inclusive that the openings 40, 49 and 50 in the disks 37, 38 and 39 are located respectively opposite the finger tabs 42, 43 and 44 and are interposed in the series of display areas upon the faces of the respective disks. It will likewise be observed by reference to Figures 22 and 23, and 24 and 25 and a comparison of these figures that the disks 38 and 39 are provided upon both faces with a series of display areas, these areas being indicated upon the two disks respectively by the numerals 51 and 52.

From the foregoing description of this embodiment of the invention it will be understood that by holding the disk 37 stationary through the medium of the finger tab 42 and simultaneously rotating the disks 38 and 39 by simultaneously grasping their finger tabs 43 and 44, the display areas 51 upon the disk 38 may be successively brought into registration with the display opening 40 of the said disk 37. It will also be understood from the foregoing description that by holding the disk 37 stationary and adjusting the disk 38 so that its opening 49 will register with the opening 40 in the disk 37 and then holding the tabs 42 and 43 stationary simultaneously and adjusting the disk 39 through the medium of the finger tab 44, the display areas 52 upon the disk 39 may be successively brought to view. It will also be evident that the device as a whole may be reversed or inverted so as to present the disk 39 uppermost as in Figure 17 whereupon the disk 39 may be held station-

ary and the disks 37 and 38 rotatably adjusted with respect thereto so as to bring the display areas 51 upon the other side of the disk 38 successively into registration with the display 5 opening 50 in the said disk 39 and likewise, as in the previously described operation, the disks 38 and 39 may be held stationary with their openings 49 and 50 in registration and the disk 37 may be rotatably adjusted so as to 10 bring its display areas 41 into successive registration with the registering openings 49 and 50. As previously stated any desired number of the disks may be connected together in interleaved relation for relative rotative adjustment, in accordance with this embodiment of the invention.

It is to be understood, of course, that various changes may be made, within the scope of what is claimed, without departing from 20 the spirit of the invention.

Having thus described my invention, what I claim is:

1. A toy comprising a cover disk having a display opening therein, a plurality of display disks each bearing an annular series of display areas, and means connecting all of said disks to provide for relative rotation of the display disks with respect to one another and with respect to the cover disk, the means 30 being located concentric to the series of display areas, the said display disks being mutually, helically interleaved, certain of the disks having openings therein through one or an assemblage of which the display areas of 35 the other disks may be viewed.

2. A toy comprising a cover disk having a display opening therein, and provided with a finger tab at its periphery, a plurality of display disks each bearing an annular series 40 of display areas, means connecting all of the disks concentrically with respect to the said series of display areas, whereby to provide for rotative adjustment of the display disks with respect to one another and with respect 45 to the cover disk and successively bring the display areas to position opposite the display opening in the cover disk, and finger tabs projecting from the said display disks at the peripheries thereof, the display disks being 50 mutually, helically interleaved, certain of the disks having openings therein through one or an assemblage of which the display areas of the other disks may be viewed.

3. A toy comprising a cover disk having 55 a display opening therein, a plurality of display disks arranged beneath the cover disk, means connecting all of the said disks axially thereof to provide for rotative adjustment of the display disks with respect to one another and with respect to the cover disk, each display disk bearing upon its face which is presented toward the cover disk, an annular series of display areas adapted to be successively brought into position opposite the display opening in the cover disk upon rotative 60

adjustment of the display disk with respect thereto, the said display disks being mutually, helically interleaved, the said display disks bearing upon their other faces display matter occupying substantially the entire 70 area of said faces and adapted to be selectively displayed upon rotative adjustment of the disks with respect one to another.

4. A toy comprising a cover disk having a display opening therein, a plurality of display disks arranged beneath the cover disk, means connecting all of said disks axially thereof to provide for rotative adjustment of the display disks with respect to one another and with respect to the cover disk, each display disk bearing upon its face which is presented toward the cover disk, an annular series of display areas adapted to be successively brought into position opposite the display opening in the cover disk upon rotative 80 adjustment of the display disks with respect thereto, the said display disks being mutually, helically interleaved, the said display disks bearing upon their outer faces display matter occupying substantially the entire 85 area of said faces and adapted to be selectively displayed upon rotative adjustment of the disks with respect one to another, and finger tabs projecting from the peripheries of the disks.

5. A toy comprising a plurality of display disks bearing matter to be displayed, and means connecting the disks for relative rotative movement about a common axis, the disks being mutually, helically interleaved, 100 one of the said disks having an opening therein through which matter on adjacent ones of the disks is displayed.

6. A toy comprising a plurality of disks, a cover disk having a display opening therein, means axially connecting all of the disks and providing for relative rotative adjustment of the display disks with respect to one another and with respect to the cover disk, the display disks being mutually, helically 105 interleaved, the said display disks each bearing upon one face an annular series of display areas concentric to the connecting means for the disks and adapted to be successively brought to position opposite the opening in the cover disk upon rotative adjustment of the respective display disk, and finger tabs projecting peripherally from all of the disks, the said display disks bearing upon their outer faces display matter occupying substantially the entire area of the said faces and adapted to be displayed substantially in its entirety through relative rotative adjustment of the said display disks.

7. A toy comprising a cover disk having a 125 display opening therein, a plurality of display disks arranged beneath the cover disk and mutually, helically interleaved, means axially connecting all of the disks whereby the display disks may be rotatably adjusted 130

with relation to one another and with relation to the cover disk, each display disk bearing upon its face which is presented toward the cover disk, an annular series of display areas adapted to be successively brought opposite the opening in the cover disk upon rotative adjustment of the said respective display disks, and resilient means upon each display disk for coaction with the adjacent disk to restrain the disk from relative movement.

8. A toy comprising a cover disk having a display opening therein, a plurality of display disks arranged beneath the cover disk and mutually, helically interleaved, means axially connecting all of the disks whereby the display disks may be rotatably adjusted with relation to one another and with relation to the cover disk, each display disk bearing upon its face which is presented toward the cover disk, an annular series of display areas adapted to be successively brought opposite the opening in the cover disk upon rotative adjustment of the said respective display disks, resilient means upon each display disk for coaction with the adjacent disk to restrain the disk from relative movement, each of the said disks being provided with a peripheral finger piece.

9. A toy comprising a plurality of display disks bearing matter to be displayed, means connecting the disks for relative rotative movement about a common axis, the disks being provided with radial incisions and being assembled by being mutually, helically interleaved, each disk being provided with a finger tab extending therefrom at its periphery and divided by the radial incision, and means

joining the finger tab portions of each disk whereby to provide a locking means to limit the relative rotative adjustment of the disks in one direction.

10. A toy comprising a cover disk having a display opening therein, a plurality of display disks each bearing an annular series of display areas, means connecting all of said disks to provide for relative rotation of the display disks with respect to one another and with respect to the cover disk, the means being located concentric to the series of display areas, the said display disks being mutually, helically interleaved, and means upon certain of the display disks for coaction with the next adjacent display disks for maintaining the disks relatively stationary.

11. A toy comprising a cover disk having a display opening therein, a plurality of display disks each bearing an annular series of display areas, means connecting all of said disks to provide for relative rotation of the display disks with respect to one another and with respect to the cover disk, the means being located concentric to the series of display areas, the said display disks being mutually, helically interleaved, and means upon certain of the display disks for coaction with the next adjacent display disks for maintaining the disks relatively stationary, the said means comprising resilient clips carried by the said disks at one margin of the incision therein and engageable with the corresponding marginal portion of the overlapping disk.

In testimony whereof I affix my signature,

CLANCY M. ROGERS.
